AUTOMATIC INFEED CENTERLESS GRINDER

Andrew J. Graf, Norwood, and Clifford L. Schulte, Rossmoyne, Ohio, assignors to Cincinnati Grinders Incorporated, Cincinnati, Ohio, a corporation of Ohio

Application July 16, 1937, Serial No. 154,046

13 Claims. (Cl. 51—103)

This invention relates to grinding machines and more particularly to improvements in automatic centerless grinders.

One of the objects of this invention is to provide an improved and simplified mechanism for obtaining greater advance and retractive movements between the grinding wheels of a centerless grinder of the infeed type.

Another object of this invention is to provide 10 an improved hydraulic operating and control mechanism for governing the movements of the regulating wheel in a centerless grinder of the infeed type.

A further object of this invention is to provide 15 an improved control mechanism for producing a complete automatic cycle in an infeed type centerless grinder, including loading and ejecting of the work, which may be controlled by a single cam.

An additional object of this invention is to provide 20 an improved automatic infeed type centerless grinder for automatic grinding of work pieces which do not lend themselves to through feed grinding principals.

Other objects and advantages of the present invention should be readily apparent by reference 25 to the following specification considered in conjunction with the accompanying drawings illustrative of one embodiment thereof, but it will be understood that any modifications may be made 30 in the specific structural details within the scope of the appended claims without departing from or exceeding the spirit of the invention.

Referring to the drawings in which like reference numerals indicate like or similar parts:

35 Figure 1 is an elevation of a centerless grinder embodying the principles of this invention.

Figure 2 is a plan view of the machine shown in Figure 1.

Figure 3 is a section through the cam controlled 40 mechanism as viewed on the line 3—3 of Figure 2.

Figure 4 is an enlarged detail section taken on the line 4—4 of Figure 3.

Figure 5 is an enlarged section taken on the 45 line 5—5 of Figure 2.

Figure 6 is an enlarged detail view of the control cam.

Figure 7 is a section through the work loading mechanism as viewed on the line 7—7 of Figure 50 1.

Figure 8 is a section on the line 8—8 of Figure 7.

Figure 9 is a diagrammatic view of the hydraulic control circuit.

55 Grinding operations on a centerless grinder are

usually carried out by two different methods, one of which is the through feed method and the other the infeed method. The through feed method is used for grinding cylindrical work, which passes through the grinding throat in a 5 continuous stream. The infeed method is utilized for grinding work pieces which either have an obstruction thereon which is larger in diameter than the portion being ground, or have a contoured surface, which necessitates their remaining in a fixed axial position relative to the wheels. When the latter method is used, the wheels must be retracted for the purpose of removing and inserting work, and then brought together to form the grinding throat, after which an additional movement or infeed is effected to accomplish the grinding operation and reduce the work to the desired size.

This invention deals with an automatic mechanism which will effect a continuous repetition of 20 an automatic infeed cycle including automatic positioning and ejecting of the work. In prior machines of this nature it was only necessary to provide a relatively small amount of separation between the wheels to permit withdrawal of the 25 work, but in the present machine the work moves laterally from the work rest blade and drops between the wheels into a conveyor chute, which means that the movable wheel must be retracted a much greater amount than heretofore in order 30 to permit work ejection in this manner. Due to this larger movement, prior mechanisms have been found inadequate and therefore an improved structure has been provided by the present invention, whereby a large movement may be 35 easily and quickly effected, and one of the features of this invention is to provide a mechanism which will execute the positioning movements at a rapid rate and the grinding movements at a desirable slow rate.

Referring to Figures 1 and 2 of the drawings, the reference numeral 10 indicates the bed of a centerless grinder having a grinding wheel 11, and a regulating wheel 12, supported on the top thereof for relative movement toward and from 45 one another, and with respect to a work rest blade 13 which is located between the wheels. On the present machine the grinding wheel 11 rotates in a fixed position, and the regulating wheel 12, which rotates at a much slower speed than the grinding wheel, and serves the function of rotating the work, is rotatably journaled on a movable slide 14 for relative movement with respect to the grinding wheel to permit insertion and removal of the work.

The slide 14, as more particularly shown in Figure 5, carries a nut 15, in which is threaded a screw 16 having an axially extending shank 17. The shank 17 has a piston 18 secured thereto which is reciprocably supported in a cylinder 19. The cylinder is integral with a bracket 20 which is attached to the bed 10. The shank 17 extends through the rear of the bracket 20 for receiving an operating hand wheel 21 which serves to rotate the screw 16 relative to the nut 15. It will now be apparent that the slide 15 may be moved, either by admitting fluid pressure to the cylinder 19, or by rotating the hand wheel 21.

The piston 18 has a somewhat limited movement within the cylinder 19, but of sufficient amount to permit the work piece to clear the work rest blade, while the hand wheel is adapted to adjust the regulating wheel the full length of its stroke and serves to position the wheel relative to the piston 18 dependent upon the diameter of the work and the amount of room necessary to clear the work rest blade, and thus acts to determine the situs of the power stroke to be effected by the piston. The piston 18 serves to move the regulating wheel toward the grinding wheel, while another piston 22 is provided for effecting the return stroke. The piston 22 is connected by a piston rod 23 to the slide 14. The cylinder 24 which contains this piston is the same length as the total stroke of the slide 14, because a relative adjusting movement between the piston 22 and the slide 14 cannot be effected as in the case of the piston 18.

The work piece being ground in this machine is indicated by the reference numeral 25 in Figure 7, and it will be noted that the work piece has a conoidal shaped end 26. The work is inserted between the grinding wheels with this end first, and the grinding wheel 11 has a parabolic shaped portion 27 which is complementary to the shape to be ground on the ends of the work piece. It is due to the converging shapes of the two grinding wheels that prevents work pieces of this nature from being ground by the through feed method.

The work pieces are stacked in a hopper 28 and a reciprocable plunger or work pusher 29 is supported adjacent to the bottom of the hopper for moving a work piece from the hopper to the grinding throat between the wheels. After the plunger has moved a work piece into the grinding throat, it remains in the dash and dot position indicated by the reference numeral 30 in Figure 7 during the grinding operation to serve as means for holding the work in proper axial position with respect to the wheel, because due to the converging shapes of the grinding wheels, an axial thrust is developed which would tend to cause the work to move backward.

The manner in which the work piece 25 is supported in the grinding throat of the machine is more particularly shown in Figure 8. It will be noted that the work rest blade 13 has an angular top 31, and that the clockwise rotation of the grinding wheel urges the work piece downward against this top and into engagement with the regulating wheel. This insures that the work will be held in sufficient frictional engagement with the regulating wheel whereby the same will cause rotation of the work in a counterclockwise direction due to the clockwise rotation of the regulating wheel. The work rest blade 13 is supported on lower slide 32 which is slidably mounted upon the bed 10, and in turn has guide surfaces formed on the top thereof for reciprocably supporting the slide 14. By clamping the slide 32 to the slide 14

the work rest blade may be adjusted to the proper position in front of the grinding wheel. The lower slide may then be clamped to the bed 10 and the upper slide moved to vary the position of the regulating wheel.

When the work has been ground to size, it will be apparent from Figure 8, that the regulating wheel 12 must be retracted a sufficient amount that the work piece 25 may fall off of the angular top work rest blade into the work receiving chute 33. It will be apparent that the amount of this movement must be equal to the distance between the side 34 of the work rest blade and a line 35 tangent to the periphery of the grinding wheel at the point of contact with the work. This distance is indicated by the reference numeral 36, and determines the minimum stroke of the piston 18 which translates the regulating wheel.

The work pusher 29 is actuated by a piston 37 contained in the cylinder 38, as shown in Figure 7, and connected by a piston rod 39 to the pusher 29. This cylinder has a pair of ports 40 and 41 at opposite ends which are connected by channels 42 and 43 respectively to ports 44 and 45 of a reversing valve indicated generally by the reference numeral 46. This reversing valve has a pressure port 47 which is supplied with fluid from a pump 48 having an intake 49 through which fluid is withdrawn from a reservoir 50. The valve also has a pair of return ports 51 and 52 which are connected to the return line 53 leading to the reservoir 50. A plunger 54 is reciprocably mounted in this valve and is held by fluid pressure into engagement with an operating arm 55 which is carried by the shaft 17. The plunger has a pair of annular grooves 56 and 57 formed therein which serve to alternately connect the pressure port 47 to ports 44 and 45 to effect alternate advance and retraction of the work pusher 29.

The advancing movement of piston 18 is controlled by a servo-valve indicated generally by the reference numeral 58 and consisting of movable sleeve 59 and an independently movable plunger 60. The sleeve has a first wide annular groove 61 which is in constant communication with a passage 62 terminating in an annular groove 63 which is in communication with the pressure port 47; a second wide annular groove 64 which is in constant communication with a channel 65 leading to the right hand end of cylinder 19; and a third annular groove 66 which is in constant communication with an exhaust channel 67. Radial holes are drilled in the groove 64 forming a port 68 which is normally closed by a spool 69 formed on the plunger 60.

The spool 69 is substantially the same width as the port 68 so that upon movement of the plunger 60 to the left, the pressure will flow from the port 47 through the passage 63, groove 61, port 68, and annular groove 66 to the port 68, 60 and thereby through the passage 65 to the cylinder 19 to cause actuation of piston 18. Upon movement of the spool to the right, the port 68 will be connected by the annular groove 72 in plunger 60, to the exhaust port 73. The plunger 60 is held into engagement with a second plunger 74 which carries a roller 75 bearing on the periphery of a cam 76. The plunger 74 is slidably mounted in the open end of sleeve 59, and a key 77 is provided for holding the plunger 74 against rotation in the sleeve so as to maintain the axis of the roller 75 parallel to the axis of the shaft 77 which supports the cam. The sleeve is fixed with the member 55. It will now be apparent that if elevations are provided on the cam that

the plunger 60 can be moved, as to the left, independently of the sleeve to cause fluid pressure to flow to cylinder 19, and that upon actuation of the piston 18, the member 55 will cause the sleeve 59 to follow up the movement of the plunger 60 and thereby close the port 68 to stop movement of the piston.

Thus the piston 18 is a servo controlled single acting piston for causing advancing movement of the regulating wheel toward the grinding wheel. Return movement of the regulating wheel is effected by the second piston 22 slidably mounted in a cylinder 24 and connected by a piston rod 23 to the regulating wheel slide 14. This piston is smaller in diameter than the piston 18 whereby a constant pressure can act thereon in one direction, the left end of the cylinder, as shown in Figure 9, having a port 81 which is connected by channel 82 to the output of pump 48. In other words, the same unit pressure of the pump is caused to act on pistons 18 and 22, but when acting on the piston 18 its larger area will produce a total resultant pressure which is greater than the total resultant pressure acting in the opposite direction on piston 22 and the slide will move toward the grinding wheel. The cylinder 24 has a length equal to the total length of possible movement of slide 14 because no adjustable connection is provided, whereas the piston 18 has a screw and nut connection with the slide 14 whereby the piston 18 may have the same starting position regardless of the longitudinal position of the slide 14 relative to the bed.

Although the shaft 17, as shown in Figure 5, carries the piston 18 and member 55 during axial movement thereof, it is not necessary or desirable that these parts rotate, when the shaft 17 is rotated manually to effect relative adjustment of the regulating wheel slide, and therefore antifriction bearing means have been provided whereby the shaft 17 may be rotated relative to these parts. To this end the shaft 17 is provided with a shoulder 83 and a reduced portion 84 upon which are mounted a pair of antifriction thrust bearings 85, one of which abuts the shoulder 83. The piston 18 has an internal annular rib 86 which projects between these thrust bearings, and a nut 87 is threaded on the rod 17 for clamping all of these parts against the shoulder 83 so that the piston is rigidly connected for axial movement of the shaft 17 while permitting the shaft to rotate without causing rotation of the piston 18.

The shaft 17 is provided with a second shoulder 88 and reduced portion 89 upon which is mounted a sleeve 90 having a shoulder at one end which is clamped against the shoulder 88 on the shaft by a locking nut 91. The sleeve carries a pair of thrust bearings 92 which antifrictionally support the member 55.

In the enlarged view in Figure 4, it will be seen that the member 55 has a rectangular slot 93 formed in the end thereof for engaging a complementary shaped portion 94 formed on the end of sleeve 59 whereby the sleeve is held against rotation. The connecting member 55 also has a depending portion 95 which carries a set screw 96 which forms an abutment for the reversing valve plunger 54, and by adjusting the screw 96 relative to the member 55, the point of reversal of the actuating piston 37 for the work loader may be accurately timed with respect to the movements of the regulating wheel.

As previously stated, the reversing valve plunger 54, and the sleeve 59 are held by constant

pressure in engagement with the connecting member 55. This pressure is hydraulic and is supplied by the pump 48, but is much lower than the pressure of the actuating fluid. This lower pressure is obtained by providing two serially arranged check valves 97 and 98 in a branch line 99 leading to reservoir from the main delivery line of pump 48, which act as serial hydraulic resistances, whereby a channel 100 connected to the line 99 between these resistances may be provided with any unit pressure between the pump pressure and atmospheric pressure. In the present case, the check valve 97 is set to have about six times as much resistance as the check valve 98 whereby the unit pressure in channel 100 will be about one-sixth of the unit pressure supplied to the piston 18. The channel 100 is connected to the spaces 101 and 102 whereby this unit pressure will act on all of members 54, 59 and 60 to hold plunger 54 and sleeve 59 in engagement with the member 55, and the plunger 60 into engagement with the periphery of the cam wheel 76. In order to take care of any leakage, the space 103 in cylinder 19, and the space 104 in cylinder 79, are connected to a return line 105 whereby any accumulation of fluid which might interfere with proper operation of the parts may be disposed of.

In order that the work loading plunger may move at a smooth, even and controlled rate, an adjustable throttle valve 106 may be interposed in the channel 43 whereby it will control the outflow from cylinder 38 during movement in one direction and the inflow during movement in the other direction and thereby control the rate of both directions of movement.

The machine has a continuously repeating automatic cycle, and the cycle of operation is controlled by the cam 76. As shown in Figure 3, an electric motor 107 is mounted on the bracket 20, and connected by a coupling 108 to shaft 109 journaled within the bracket. A spur gear 110 is keyed to the end of this shaft for driving gear 111 keyed to the end of shaft 112. The latter shaft carries a worm 113 intermeshing with a worm gear 114 keyed to the cam driving shaft 71. It will now be apparent that upon actuation of the motor 107, that the cam shaft will be continuously rotated at a uniform rate.

The cycle of operation of the machine will be explained, reference being had to the enlarged view of the control cam 76, as shown in Figure 6. The radial line 115 indicates the starting point, and the arrow 116 indicates the direction of rotation of the cam. The valve plungers 54 and 60 are shown in the starting position in Figure 9, and it will be noted that the port 41 of cylinder 38 is connected to pressure to cause retraction of the work pusher. Assuming the retractive movement to begin at the line 115 on the cam, it will be apparent that an appreciable length of time at least will be necessary to complete this movement, and therefore the cam is provided with a dwell 117 to insure completion of this movement. When completed, the parts will be in the position shown in Figure 7, and a new work piece 25 will drop from the hopper 28 into a position in front of the pusher 29.

It is to be understood that the plunger 60 and sleeve 59 constitute what is commonly termed a servo-motor mechanism in that displacement of the plunger 60 to the left, as viewed in Figure 9, by action of cam 76, introduces pressure by way of groove 61, port 70, groove 71 and port 65 to the right hand side of piston 18, moving mem-

ber 17 and associate parts to the left. As sleeve 59 is coupled through member 55 with 17, it is correspondingly shifted to the left, restoring the alignment of port 68 with valve land 69, causing discontinuance of this movement. As the land and port form a variable throttle or resistance, the extent of their displacement determines the rate of actuation of the piston.

The sharper the rise on cam 76 which is rotated at a uniform rate, the faster the rate of movement of the plunger 60 and consequently the faster the follow-up of member 17 and sleeve 59. Conversely, on reverse movement of the plunger, land 69 couples port 68 via cannelure 72 with exhaust conduit 67, variably throttling the relief of pressure on the right hand side of piston 18, permitting retraction of parts by the pressure in cylinder 24, the reverse follow-up of sleeve 59 correspondingly controlling the rate and extent of this retracting movement.

The cam is next provided with a rapidly rising portion 118 which will cause movement of the servo-valve plunger 60 to the left as viewed in Figure 9, thereby admitting fluid to cylinder 19 which will cause movement of piston 18 and thereby move the regulating wheel toward the grinding wheel a sufficient amount to contract the grinding throat, Figure 8, in readiness for insertion of the next work piece. During the advancing movement of piston 18, the connecting member 55 has been following up the movement of the servo-valve plunger 60 and has been moving the reversing valve plunger 54 toward the left so that by the time the point 119 is reached on the cam 76, the reversing valve plunger 54 has been moved a sufficient distance to connect pressure port 47 to port 44. The piston 31 now advances to insert a new work piece into the grinding throat and in order to permit this movement to be completed, a dwell 120 is provided on the cam. The work is now ready to be ground and a short sharp rise 121 is provided on the cam for moving the work into contact with the grinding wheel.

45. A slow rising portion 122 is next provided on the cam whereby the regulating wheel slowly advances the work into the grinding wheel to reduce the work to size. In order to permit the grinding wheel time to clean up the work and spark out after the advancing movement of the regulating wheel has been completed, the dwell 123 is provided. With the work now ground to size, a sudden fall 124 is provided on the cam which permits the servo-valve plunger 60 to move toward the right, and connect port 68 to exhaust port 73 whereby the constant pressure in cylinder 24 may now retract the regulating wheel through action on the piston 22. By the time the retracting movement has completed, and the work has dropped off of the work rest blade into the chute 33, the reversing valve plunger 54 has moved to such a position that the pressure port 47 is connected to port 45 to cause retraction of the work pusher and the next cycle of operation is ready to begin. It will now be apparent that the cam controls the rapid advance and feeding movement of the regulating wheel as well as the return movement thereof, and also causes insertion of a new work piece by power at the proper moment in the cycle.

70. There has thus been provided an improved power operable automatic mechanism for effecting an infeed cycle on a centerless grinding machine, including mechanism for automatically loading and ejecting the work.

What is claimed is:

1. In a grinding machine having a bed, a slide reciprocably mounted on said bed, and an abrasive wheel rotatably supported on said slide for movement to and from a work piece, the combination of means for actuating said slide, including a piston and cylinder, one of which is fixed and the other connected to said slide, a second cylinder and piston having one of said parts connected to the bed and the other to said slide, a source of fluid pressure permanently connected to one of said pistons, a servo control valve for governing the flow of fluid from said source of pressure to the other piston, including a relatively movable sleeve and plunger, a cam for actuating said plunger, fluid operable means for maintaining said plunger in contact with the periphery of said cam, and a feed back connection from one of said pistons to said sleeve.

2. In a grinding machine having a bed, a slide reciprocably mounted thereon, and an abrasive wheel rotatably mounted on said slide, the combination of means for shifting said slide, including a pair of differential pistons permanently connected to said slide, a source of fluid pressure, means permanently connecting said source of fluid pressure to the smaller of said pistons, and a servo control valve mechanism for controlling the flow of fluid to and from the other of said pistons to cause advance and retraction of said slide.

3. In a grinding machine having an abrasive wheel, the combination of fluid operable means for advancing and retracting the wheel with respect to a work piece, a fluid operable work loader for successively positioning work pieces in front of said wheel, a reversing valve plunger for said work loader, means continuously urging said plunger in one direction to cause retraction of said work loader, and means operable during advancing movement of said wheel to positively shift said reversing valve in an opposite direction and cause said work loader to position a work piece in front of said wheel.

4. In an automatic infeed centerless grinder, the combination with a bed supporting a grinding wheel, a work rest blade and a regulating wheel, of a cam rotatably mounted on said bed, a prime mover, a motion transmitting train coupling the prime mover for rotation of said cam, a cam follower, fluid operable means for maintaining said follower in contact with the periphery of said cam, an infeed mechanism for said regulating wheel coupled for control by said follower, a work loader coupled for control by said follower, a first portion on said cam for causing rapid advance of said regulating wheel to form a grinding throat and initiate a work loading operation, a dwell on said cam for permitting the work loading operation to be completed, a second portion on said cam for rapid advancing and slowly feeding said regulating wheel toward the grinding wheel to effect a grinding operation, a second dwell on said cam to permit said grinding wheel to spark out, and a third portion on said cam for causing retraction of the regulating wheel and ejection of the finished work piece.

5. A precision grinding machine including a grinding member, a work positioning member, means for positioning work for joint engagement by said members, one of said members being movable relative to the other to effect the grinding action, and means for controlling said movement, including a pair of oppositely acting hydraulic motors, a hydraulic pressure source, means cou- 75

- pling said source with one of said motors for constant unidirectional actuation thereof, and means for coupling hydraulic actuating medium to the other of said motors, said coupling means including mechanism for variably determining the rate of change and effective pressure differential in the respective hydraulic motors and thus the rate and relative direction of movement of the grinding and work engaging members.
6. A precision grinding machine including a grinding member, a work positioning member, means for positioning work for joint engagement by said members, one of said members being movable relative to the other to effect the grinding action, and means for controlling said movement, including a pair of oppositely acting hydraulic motors, a hydraulic pressure source, means coupling said source with one of said motors for constant unidirectional actuation thereof, and means for coupling hydraulic actuating medium to the other of said motors, said coupling means including mechanism for variably determining the rate of change and effective pressure differential in the respective hydraulic motors and thus the rate and relative direction of movement of the grinding and work engaging members, said means including a reciprocable throttling plunger, means for controlling the reciprocation of said plunger, a sleeve valve encircling the plunger, and connections between the movable member and the sleeve whereby movement of the member shifts the sleeve to counteract the initial displacement of the plunger with respect thereto.
7. A precision grinding machine including a grinding member, a work positioning member, means for positioning work for joint engagement by said members, one of said members being movable relative to the other to effect the grinding action, and means for controlling said movement, including a pair of oppositely acting hydraulic motors, a hydraulic pressure source, means coupling said source with one of said motors for constant unidirectional actuation thereof, means for coupling hydraulic actuating medium to the other of said motors, said coupling means including mechanism for variably determining the rate of change and effective pressure differential in the respective hydraulic motors and thus the rate and relative direction of movement of the grinding and work engaging members, said means including a reciprocable throttling plunger, means for controlling the reciprocation of said plunger, a sleeve valve encircling the plunger, and connections between the movable member and the sleeve whereby movement of the member shifts the sleeve to counteract the initial displacement of the plunger with respect thereto, and means reacting on the plunger to prevent frictional shifting thereof by movement of the sleeve.
8. A precision grinding machine including a grinding member, a work positioning member, means for positioning work for joint engagement by said members, one of said members being movable relative to the other to effect the grinding action, and means for controlling said movement, including a pair of oppositely acting hydraulic motors, a hydraulic pressure source, means coupling said source with one of said motors for constant unidirectional actuation thereof, means for coupling hydraulic actuating medium to the other of said motors, said coupling means including mechanism for variably determining the rate of change and effective pressure differential in the respective hydraulic motors and thus the rate and relative direction of movement of the grinding and work engaging members, said means including a reciprocable throttling plunger, means for controlling the reciprocation of said plunger, a sleeve valve encircling the plunger, and connections between the movable member and the sleeve whereby movement of the member shifts the sleeve to counteract the initial displacement of the plunger with respect thereto, and means reacting on the plunger to prevent frictional shifting thereof by movement of the sleeve.
9. A control mechanism for determining the timed sequential operation of the shiftable parts of an automatic centerless grinder including relatively movable grinding and regulating wheels and a work shifting mechanism for intermittently positioning a work piece between the wheels, including a uni-directionally activated hydraulic motor coupled with one of the wheels of the machine for effecting their relative movement, means continuously actuating said wheel in opposition to said motor, a source of hydraulic pressure, and means for controlling the introduction and exhaust of hydraulic pressure from the motor including a shiftable sleeve coupled with and movable by the motor, said sleeve having spaced pressure and exhaust grooves, ports coupling these grooves with the interior of the sleeve, a plunger valve contained within the sleeve and variably determining the effective coupling of the ports with the motor, and a continuously driven variably contoured cam reacting on the plunger whereby power positioning of the motor and sleeve and thus of the associated wheel of the machine will be variably effected by hydraulic power in accordance with the cam contour determined positioning of the plunger.
10. A control mechanism for determining the timed sequential operation of the shiftable parts of an automatic centerless grinder including relatively movable grinding and regulating wheels and a work shifting mechanism for intermittently positioning a work piece between the wheels, including a uni-directionally activated hydraulic motor coupled with one of the wheels of the machine for effecting their relative movement, means continuously actuating said wheel in opposition to said motor, a source of hydraulic pressure, and means for controlling the introduction and exhaust of hydraulic pressure from the motor including a shiftable sleeve coupled with and movable by the motor, said sleeve having spaced pressure and exhaust grooves, ports coupling these grooves with the interior of the sleeve, a plunger valve contained within the sleeve and variably determining the effective coupling of the ports with the motor, a continuously driven variably contoured cam reacting on the plunger whereby power positioning of the motor and sleeve and thus of the associated wheel of the machine will be variably effected by hydraulic power in accordance with the cam contour determined positioning of the plunger.

a supplemental hydraulic motor for controlling actuation of the work shifting mechanism, and means operable by the first plunger controlled motor for determining the cyclic timing and direction of actuation of said second motor.

11. A control mechanism for determining the timed sequential operation of the shiftable parts of an automatic centerless grinder including relatively movable grinding and regulating wheels and a work shifting mechanism for intermittently positioning a work piece between the wheels, including a uni-directionally activated hydraulic motor coupled with one of the wheels of the machine for effecting their relative movement, means continuously actuating said wheel in opposition to said motor, a source of hydraulic pressure, and means for controlling the introduction and exhaust of hydraulic pressure from the motor including a shiftable sleeve coupled with and movable by the motor, said sleeve having spaced pressure and exhaust grooves, ports coupling these grooves with the interior of the sleeve, a plunger valve contained within the sleeve and variably determining the effective coupling of the ports with the motor, a continuously driven variably contoured cam reacting on the plunger whereby power positioning of the motor and sleeve and thus of the associated wheel of the machine will be variably effected by hydraulic power in accordance with the cam contour determined positioning of the plunger, a supplemental hydraulic motor for controlling actuation of the work shifting mechanism, means operable by the first plunger controlled motor for determining the cyclic timing and direction of actuation of said second motor, and independent means for determining the rate of actuation of said second motor.

12. In a machine of the character described, the combination with a translatable wheel bearing support, of means for controlling translatory movements of the support, including a limited stroke hydraulic motor having an element movable with the wheel support and a fixed element, a valve sleeve fixed for movement with the element, a plunger valve supported within the sleeve and freely movable with respect thereto, means for supplying hydraulic actuating medium to the motor by way of said plunger and sleeve valves, said plunger having a projecting actuating portion, and a cam member having a contoured sur-

face engaging the plunger and movable in a definite path with respect thereto, said contours corresponding to the degrees of movement to be imparted by the motor to the translatable wheel support, said plunger and sleeve valves having interengaging portions shutting off flow with respect to the hydraulic motor when motor movement of the sleeve shifts the latter into phase relation with the cam determined position of the plunger.

13. A centerless grinder for the purpose described embodying opposed grinding and regulating wheels, an intermediate work support and an additional shiftable terminal work engaging member, all adapted for simultaneous engagement with a work piece during the grinding operation, and means for controlling the engagement and release of the work by said parts, including a first hydraulic motor for effecting movement of the terminal work engaging member and a second hydraulic motor mechanism for effecting back and forth movement of one of said wheels, said second motor mechanism including a hydraulic piston, a first valve mechanism having an extended idle stroke and terminal effective positions for controlling reversal of the terminal work engaging member, an activating member operable by the second motor and provided with means for operating said first valve, and a servo-motor mechanism for positional control of said second motor including a sleeve valve member carried and shiftable by the activating member, a contained plunger valve within the sleeve and shiftable in exact accordance with the actuating movement to be imparted to said second motor, a rotor cam engageable with said plunger member, means for effecting continuous rotation of the cam, and hydraulic means for maintaining the plunger in engagement with the cam, said cam having an eccentrically contoured plunger engaging surface having successive concentric and eccentric portions of increasing radii throughout the major portion of its circumference whereby successive dwells and progressively advancing movements are imparted to the plunger and hydraulically transmitted through the motor to the shiftable wheel unit substantially as and for the purpose described.
